DUAL WHEEL ASSEMBLY

Charles S. Ash, Milford, Mich.

Application May 7, 1943, Serial No. 486,014

9 Claims. (Cl. 188—18)

1

The present invention relates to dual wheel assemblies and more particularly to assemblies in which the wheels are independently relatively rotatable.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a vertical sectional view showing a typical and illustrative embodiment of the present invention;

Fig. 2 is an elevation taken along line 2—2 of Fig. 1;

Fig. 3 is a sectional view taken along line 3—3 of Fig. 2; and

Fig. 4 is a sectional view of a modified form of the present invention.

It is an object of the present invention to provide an improved dual wheel assembly in which the two wheels are independently relatively rotatable. A further object is to provide such an assembly with improved braking means. The invention further provides improved vehicle wheel brakes which are sturdy, dependable and serviceable and which afford little or no friction in the anchoring or mounting of the brake shoe means. Still another object of the present invention is the provision of balanced, adequate, long wearing and relatively frictionless brakes for independently relatively rotatable dual wheel assemblies.

With the stated and other objects in view there is provided, in an illustrative embodiment of the invention as shown by way of example in the accompanying drawings, a pair of side-by-side wheels mounted at the end of a vehicle axle. The hub of one wheel is mounted for rotation by means of suitable bearings on the axle end,

2

and the hub of the other wheel is mounted on the exterior of the first hub for independent relative rotation.

The inner wheel of the assembly is provided with a frusto-conical brake drum at its inner side, with which a correspondingly shaped brake shoe is engageable by axial movement of the shoe. A second frusto-conical brake shoe is provided between the inner and outer wheels, and this shoe is likewise carried by the inner wheel, the shoe and drum being connected and mounted on the wheel for axial movement. The outer wheel web is formed in a frusto-conical shape adjacent the second brake shoe as a brake drum for the shoe. Hydraulic actuating means are provided to force the first brake shoe into braking engagement with the first brake drum, and at the same time the second brake shoe into engagement with the second brake drum. The 10 brake drums and shoes are correspondingly formed and positioned having their smaller diameters outwardly of the assembly and their larger diameters inwardly.

A brake anchoring member is provided at the 15 inner side of the inner wheel on the axle and carries a pair of links pivotally mounted thereon which are pivotally secured at their other ends to the first brake shoe, whereby the shoe is securely held against rotation but is allowed 20 limited axial movement.

In a modified embodiment of the invention the anchoring means for the first brake shoe comprises a metal annulus secured to the shoe at its outer periphery and to the axle at its inner periphery. The brake shoe is thus held against 25 rotation but may have limited axial movement into engagement with its brake drum by flexing the metal anchoring annulus.

It will be understood that the foregoing general description and the following detailed description as well are exemplary and explanatory of the invention but are not restrictive thereof.

Referring now in detail to the illustrative embodiment of the present invention shown in Fig. 1 of the accompanying drawings, a vehicle axle 10 has a reduced end 11 upon which a dual wheel assembly is mounted. The inner wheel web 15 of the assembly has an elongated outwardly extending hub 16 which is mounted for rotation on the axle end 11 by means of anti-friction bear-

ings 17 and 18. The inner bearing 17 is seated against a shoulder 19 of the vehicle axle and against a shoulder 20 of the hub, while the outer bearing 18 is seated against another shoulder 21 of the hub. Nuts 22 and washers 23 on the end of the axle securely position the inner wheel hub and bearing assembly. A packing ring 24 and annular guard plate 25 may be positioned at the inner end of the hub 16 to protect the bearings from dirt and loss of oil.

The outer wheel web 30 has an inwardly extending hub 31 which is journalled on the outer finished surface of hub 16 for independent relative rotation, cylindrical bushing 32 being interposed between the hubs. Hub 31 is held against axial thrust by a shoulder 33 of inner hub 16 and by ball bearing 34. Retaining nut 35 threaded on the end of hub 16 securely positions the outer hub assembly, and a cap 36 may be placed over the end of the assembly for protection of the bearings.

The wheel webs 15 and 30 are each provided with a plurality of spoke members 40 and mounting bolts 41, whereby pneumatic tire carrying rims 42 may be mounted on their respective wheels by means of lugs 43.

The braking means for the dual wheels comprise a frusto-conical brake drum 50 positioned at the inner side of the inner wheel web 15. The drum 50 is mounted on this wheel web for correlative rotation therewith by means of a plurality of guide rods 51 which extend through bushed apertures 52 in the wheel web. At their other ends the guide rods 51 carry a frusto-conical brake shoe 55, so that drum 50 and shoe 55 are carried by the inner wheel web 15 and are axially movable with respect thereto.

A frusto-conical brake shoe 56 having molded brake lining 57 is provided for engagement with the inner brake drum 50, and is actuated by hydraulic cylinders 58. The cylinders have pistons 59 adjustably secured to the brake shoe by means of threaded rods 60, and are mounted on anchor arms 61 which are fast on the vehicle axle 10.

The outer wheel web 30 is formed at its radially outer portion in a frusto-conical brake drum portion 65, and brake shoe 55 has molded brake lining 66 on its exterior surface for engagement therewith.

Thus actuation of brake shoe 56 into engagement with drum 50 for braking the inner wheel will at the same time actuate the outer brake shoe 55 into engagement with the brake drum portion 65, providing for the braking of the outer wheel with the inner wheel. The brake drums and shoes are correspondingly formed and positioned so that their wider openings or diameters are inwardly of the assembly and of the vehicle and their smaller openings or diameters are outwardly. Thus in braking the wheels of the assembly the smaller members 56 and 55 of the braking mechanism are forced by outwardly directed axial force into the larger members 50 and 65.

The outer wheel web 30 is formed at its outer periphery in an inwardly axially extending cylindrical portion 70 which is enclosed by an outwardly axially extending cylindrical portion 71 of the periphery of the inner wheel web 15, and an annular sealing washer 72 is positioned in a groove in portion 70. The braking mechanism between the wheels is thus effectively protected against dust and dirt. Moreover, the major portion of the space between the wheels is thus closed off from the accumulation of rocks, chunks of dirt, etc., which is extremely troublesome in con-

ventional dual wheel constructions, and a cylindrical outer surface is provided to aid in keeping the assembly from sinking in mud and sand.

5 Sturdy and substantially frictionless brake anchoring means are provided in the assembly, and as embodied comprise the anchor arms 75 which are secured to axle 10 and extend vertically upwardly and downwardly therefrom. Each arm 75 has secured at its outer end a pivot pin 76 on which an anchor link 77 is mounted. A spring 78 on the end of each pin 76 holds the links 77 in place. The inner brake shoe 56 is provided with a pair of slotted hangers 79 and pivot pins 80 which receive the other ends of anchor links 77, thus pivotally mounting the links on the brake shoe.

10 The pins 80 are substantially radial of shoe 56 and substantially parallel to the other pivot pins 76 when the brakes are in retracted position. A 20 coiled spring 81 between brake drum 55 and wheel web 15, and another coiled spring 82 between brake shoe 56 and an arm 61 maintain the brake shoes and drums out of engagement except when purposely actuated.

15 The brake shoes 56 and 65 and the brake drums 50 and 55 may be formed to a close accuracy because of their frusto-conical shape and will be positioned in very close adjacency to their co-operating brake members when the brakes are retracted. A very slight axial movement of the members 50, 55 and 56 is thus involved in applying the brakes.

25 The links 77 are mounted on pivot pins 76 with ample tolerance to allow for the necessary axial movement of brake shoe 56, and springs 78 take up any looseness which may result.

30 As will be seen by reference to Figure 2, presuming the wheels to be travelling clockwise, when shoe 56 is actuated into engagement with drum 50 there will be a tendency for shoe 56 to revolve clockwise due to frictional engagement therewith. The outward axial movement of shoe 56 has placed pins 80 axially outward of pins 76 and the clockwise force in shoe 56 is divided by 35 links 77 into opposed counterclockwise and axially outward forces based on pins 76, the outward forces acting over links 77 to augment the braking action of shoe 56. The frictionally produced force producing this so-called servo action is most 40 effectively utilized to produce outward axial force when the linkage is located entirely inwardly of the surfaces of the brake elements 50, 57 whose frictional engagement produce the force.

45 A modified embodiment of the anchoring means 55 of the present invention is illustratively shown in Fig. 4 of the drawings. As there embodied, a metal annulus 85 is provided preferably having a plurality of circumferential corrugations to give added strength and resiliency to the member. 50 The annulus 85 is secured at its inner periphery to an integral flange 86 of axle 10, and at its outer periphery to inwardly extending projections 87 of brake shoe 56. The shoe is thus securely held against rotary movement, but is 55 capable of axial movement sufficient to engage the brakes of the assembly.

The invention in its broader aspects is not limited to the specific mechanisms shown and described but departures may be made therefrom 60 within the scope of the accompanying claims without departing from the principles of the invention and without sacrificing its chief advantages.

65 What I claim is:

70 1. A dual wheel brake for coaxial, independ-

ently rotatable wheels including, in combination, a brake member of conical form carried by the outer wheel, a second brake member of corresponding shape carried by the inner wheel and engageable with the first member, a third conical brake member carried by the inner wheel, a fourth member of corresponding shape engageable with the third member, and anchoring means for the fourth member including an anchored member held against rotation, and a link pivotally mounted on the anchored member and the fourth member.

2. A dual wheel brake for coaxial, independently rotatable wheels including in combination a brake member of conical form carried by the outer wheel, a second brake member of corresponding shape carried by the inner wheel and engageable with the first member, a third conical brake member carried by the inner wheel and an anchored brake member of corresponding shape engageable therewith, said brake members having their greater diameters inwardly of the assembly.

3. In a braked dual wheel assembly having coaxial, side-by-side independently rotatable wheels, the combination of a non-rotatable support on which the wheels are rotatably mounted and a pair of frusto-conical brake members for each wheel, one pair on either side of the inner wheel, one brake member being fast to the outer wheel and another fast to the support and means for relatively axially moving the brake members of each pair, said brake members having their greater diameters inwardly of the assembly.

4. A dual wheel brake for coaxial independently rotatable wheels including in combination a brake member of conical form carried by the outer wheel, a second brake member of corresponding shape carried by the inner wheel and engageable with the first member a third conical brake member carried by the inner wheel, a fourth brake member of corresponding shape engageable with the third member and a resilient anchoring member held against rotation connected to the fourth member holding said member against rotation but allowing axial movement thereof.

5. In a braked wheel assembly, an axle, a rotatable wheel, an outer braking member on the wheel having an inner peripheral frusto-conical braking surface, an inner braking member axially movable toward and from the outer braking member and having an outer peripheral frusto-conical braking surface for engagement with the braking surface thereof, said braking surfaces being generated about an axis extending generally in the direction of the axis of the wheel and having their greater diameters facing inwardly of the wheel assembly, an anchoring member fixed to the axle against rotation relatively to the wheel, and having portions extending radially of the wheel beyond opposite sides of the axle and a pivotal connection between each of said portions of said anchoring member and the inner braking member comprising a pin on the anchoring member portion inclined to the vertical plane of the wheel a pin on the inner braking member extending inward radially therefrom so as to lie substantially parallel with the first-named pin in the retracted position of the inner braking member and a link connected at its opposite ends with the respective pins.

6. In a braked wheel assembly, an axle, a rotatable wheel, an outer braking member on the wheel having an inner peripheral frusto-conical braking surface, an inner braking member axially

movable toward and from the outer braking member and having an outer peripheral frusto-conical braking surface for engagement with the braking surface thereof, said braking surfaces being generated about an axis extending generally in the direction of the axis of the wheel and having their greater diameters facing inwardly of the wheel assembly, an anchoring member fixed to the axle against rotation relatively to the wheel and having arms extending vertically above and below the axle and pivotal connections between the anchor arms and the inner braking member on opposite sides of the axial center of the wheel, each consisting of a pin on an anchoring arm inclined to the vertical plane thereof, a pin on the inner braking member extending inward radially therefrom so as to lie substantially parallel with the first-named pin in the retracted position of the inner braking member, and a link connected at its opposite ends with the respective pins.

7. In a braked wheel assembly, a rotatable wheel, an outer brake member on the wheel having an inner peripheral frusto-conical braking surface, an inner braking member axially movable toward and from the outer braking member and having an outer peripheral frusto-conical braking surface for engagement with the braking surface thereof, said braking surfaces being generated about an axis extending generally in the direction of the axis of the wheel and having their greater diameters facing inwardly of the wheel assembly and anchoring means for the inner braking member comprising an anchoring member held against rotation relatively to the wheel, a pair of pivot pins one inclined to the plane of and carried by the anchoring member and the other carried by the inner braking member and extending inward radially therefrom, and a link pivotally connected at its opposite ends with the respective pins.

8. In a braked wheel assembly, a rotatable wheel, an outer braking member on the wheel having an inner peripheral frusto-conical braking surface, an inner braking member axially movable toward and from the outer braking member and having an outer peripheral frusto-conical braking surface for engagement with the braking surface thereof, said braking surfaces being generated about an axis extending generally in the direction of the axis of the wheel and having their greater diameters facing inwardly of the wheel assembly, and anchoring means for the inner braking member comprising an anchoring member held against rotation relative to the wheel, and link connections between said inner braking member and the anchoring member on opposite sides of the axial center of the wheel, each consisting of a pair of pivot pins one inclined to the vertical plane of the wheel and carried by the anchoring member and the other carried by the inner braking member and extending inwardly radially therefrom, and a link pivotally connected at its opposite ends with the respective pins.

9. A dual brake for coaxial independently rotatable wheels, including in combination a brake member of conical form carried by the outer wheel, a second brake member of corresponding shape carried by the inner wheel and engageable with the first member, a third conical brake member carried by the inner wheel, a brake member of corresponding shape engageable therewith, said brake members having their greater diameters inwardly of the assembly, an

2,425,856

7

anchor member, and anchor link conenctions between the last named brake member and the anchor member.
